UNITED STATES PATENT OFFICE

FRIEDRICH EHRHARDT AND CHRISTIAN ROEDER, OF NUERMBERG, GERMANY

LEAD PENCIL AND LIKE POLISHING MACHINE

Application filed November 10, 1930, Serial No. 494,818, and in Germany July 23, 1930.

This invention relates to a machine for polishing lead pencils and the like and of the kind wherein the articles are automatically returned to the polishing apparatus for renewed treatment, and the invention consists in the provision of a conveying element moving in a vertical plane in front of and at right angles to guide-ways along which the pencils are delivered from and fed to the polishing apparatus, said conveying element being provided with pivotally suspended, weight-balanced hoppers which it passes up through the delivery guide-way for taking pencils therefrom and down through the feed 10 guide-way for depositing the pencils on the latter.

By this arrangement the return of the articles to the polishing apparatus will be effected in a simple, smooth and efficient 20 manner.

Fig. 1 of the accompanying drawings represents a side view of the essential parts of the machine,

Fig. 2 is a front view of the same,

Fig. 3 is a top view of the machine,

Fig. 4 is a cross section of one of the guide-ways, and

Fig. 5 is a side view on an enlarged scale of one of the hoppers.

The machine comprises a principal frame 1 carrying a polishing apparatus 3 through which the lead pencils or similar rod shaped articles are pushed in known manner from a hopper 2 on to an endless travelling drying apron 5. The latter consists of two spaced bands which are guided and moved by rollers 4 and 6. The shaft carrying the rollers 6 also carries a vaned wheel 9 the vanes of which engage between the bands 5 and between the pencils and ensure a correct delivery of the latter on an endless conveying apron 10 arranged under the apron 5 and travelling in the opposite direction. A guard plate 7 embraces the outer part of the wheel 9 and retains the pencils between the vanes until they reach the proper delivery position. The apron 10 is guided on and moved by rollers 8 and 11 and is supported either by rollers 12 or by table top 13. The apron 10 delivers the pencils on to a guide-

way 14 composed of two spaced angular members which support the pencils only at the ends thereof. A similar guide-way 15 is arranged on a level with the hopper 2 for feeding the pencils into the latter. The cross sectional form of the guide-ways 14 and 15 is illustrated in Fig. 4.

Arranged in front of the guide-ways 14 and 15 is an endless conveying element 18 which is guided by rollers in a rectangular path and in a vertical plane at right angles to the guide-ways, the guide rollers being carried by a frame 17. Horizontal shafts 20, held rotatably in bearings 21 in the conveying element 18, carry hoppers 19 which are moved by the conveying element up through the guide-way 14 and down through the guide-way 15. Weights 22, secured to the shafts, maintain the hoppers in an upright position. Each hopper 19 consists of a pair of diverging wings between which the pencils are caught as the hopper passes up between the members of the guide-way 14. Thus filled with pencils the hopper ascends with the conveying element at one side of the machine and descends at the other side thereof where it deposits the pencils on the guide-way 15 as it passes between the members of the latter. The weights 22 are bevelled, and the sides 19' of the hoppers are substantially aligned with the bevelled sides of the weights so as to form wedges which, as the hoppers descend through the guide-way 15, push the pencils in the latter towards the hopper 2. A conveying band 16 may be arranged in the guide-way 15 for feeding the pencils into the hopper 2, but this conveying band may be omitted if the guide-way is inclined so as to cause the pencils to roll along it into the hopper 2.

Means may be provided for reversing the pencils during the return travel so that their ends will be alternately leading and trailing on passing through the polishing apparatus. For this purpose the hoppers 19 are supported in the shafts 20 so as to be capable of rotation about their vertical axes and connected to pinions 23 whereby they can be rotated. For engagement with the pinions, a horizontal rack 24 is carried at the upper end of the frame 17, the rack being adapted to turn the

hoppers through 180° while they travel through the upper horizontal part of the path.

In order to discharge from the hoppers 19 pencils which fail to be taken up by the guideway 15, an abutment 25 is arranged at the foot of the frame 17 in position to engage and trip the hopper. Another abutment 26 is provided for steadyng the hoppers before they 10 reach the guide-way 14.

We claim:

1. In a lead pencil and like polishing machine, a device for receiving the pencils from and returning them to the polishing apparatus, comprising a pair of guide-ways arranged in different vertical planes and at different levels, one for feeding pencils to and the other for delivering pencils from the polishing apparatus, each guideway comprising 15 a pair of spaced angular members an endless travelling conveying element moving in a vertical plane and along a rectangular path in front of and at right angles to said guideways, and weight-balanced hoppers suspended 20 pivotally from said conveying element, each hopper comprising a pair of upwardly diverging wings arranged at right angles to said angular guide members and shorter than the space between said members, and said conveying element adapted to pass the hoppers up through the delivery guide-way for taking 25 pencils therefrom, and down through the feed guide-way for depositing the pencils on the latter.
- 35 2. The structure claimed in claim 1 in combination with means for tripping the hoppers and means for steadyng the hoppers before they ascend through the delivery guide-way.
3. A structure as claimed in claim 1 where- 40 in the hoppers and their balance weights are wedge-shaped and have a feeding effect on the pencils disposed in the feed guide-way.
4. A structure as claimed in claim 1 where- 45 in the hoppers are rotatable about their vertical axes, a pinion connected to each hopper and centered in respect of the vertical axis thereof, and a horizontal rack arranged in the upper horizontal path of the pinion, said rack adapted to engage the pinions and turn 50 the hoppers through 180°.
